UNITED STATES PATENT OFFICE

95,722

DESIGN FOR A DRESS

Irving A. Winter, Woodmere, N. Y.

Application April 26, 1935, Serial No. 56,582

Term of patent 3½ years

To all whom it may concern:

Be it known that I, Irving A. Winter, a citizen of the United States of America, residing in Woodmere, county of Queens, and State of New York, have invented a new, original, and ornamental Design for a Dress, of which the following is a specification, reference being had to the accompanying drawing, forming part thereof, wherein, new design.

The diagonal lines on the front and back of the collar represent a contrasting material.

I claim:

The ornamental design for a dress, substantially as shown and described.

IRVING A. WINTER.
